PILLOW

Margot H. Smith, Manhasset, N. Y.

Application September 15, 1949, Serial No. 5,017

Term of patent 7 years

(Cl. D3—9)

To all whom it may concern:

Be it known that I, Margot H. Smith, a citizen of the United States, residing at Manhasset, in the county of Nassau and State of New York, have invented a new, original, and ornamental Design for a Pillow, of which the following is a specification, reference being had to the accompanying drawing, forming a part hereof.

Fig. 1 is a perspective view of the front of a pillow showing my new design; and

Fig. 2 is a perspective view of the side and rear of the pillow on a reduced scale.

Fig. 3 is a perspective view of the side of the pillow on a reduced scale.

I claim:

The ornamental design for a pillow, as shown.
MARGOT H. SMITH.
